UNITED STATES PATENT OFFICE.

JOHN CLIFTON KINSLEY, OF CHICAGO, ILLINOIS.

STAKE-POCKET.

SPECIFICATION forming part of Letters Patent No. 616,940, dated January 3, 1899.

Application filed October 20, 1898. Serial No. 694,129. (No model.)

To all whom it may concern:

Be it known that I, JOHN CLIFTON KINSLEY, a citizen of the United States, residing at Chicago, in the county of Cook and State of Illinois, have invented a new and useful Stake-Pocket, of which the following is a specification.

The invention relates to improvements in stake-pockets.

10 The object of the present invention is to improve the construction of stake-pockets and to provide a simple, inexpensive, and durable one adapted to support the sides of a car and prevent the same from bulging and capable of retaining the side sills in position.

A further object of the invention is to provide a stake-pocket of this character which may be readily applied to old cars as well as to those in process of construction.

20 The invention consists in the construction and novel combination and arrangement of parts, as hereinafter fully described, illustrated in the accompanying drawings, and pointed out in the claims hereto appended.

25 In the drawings, Figure 1 is a side elevation of a portion of a car provided with stake-pockets constructed in accordance with this invention. Fig. 2 is an enlarged side elevation of one of the stake-pockets, the car being shown 30 in section. Fig. 3 is a plan view of the same. Fig. 4 is a front elevation. Fig. 5 is a transverse sectional view of the base-plate of the stake-pocket. Fig. 6 is a reverse plan view of the stake-pocket.

35 Like numerals of reference designate corresponding parts in all the figures of the drawings.

1 designates a stake-pocket constructed of malleable iron or other suitable metal and 40 having a vertical socket adapted to receive a stake 2 in the usual manner and having an inclined upper edge 3 extending upward and outward from the adjacent side 4 of a car 5. The stake-pocket extends downward below 45 the lower edges of the sides 4, and its lower portion is provided with grooves formed by ribs 6 and receiving a pair of upper and lower staples 7, which extend through the side sill 8 of the car and are secured to the same by 50 nuts 9. Instead of employing a pair of staples for securing the lower portion of the stake-pocket to the car a single staple may be used,

if desired. The upper portion of the stake-pocket is secured to the adjacent side 4 of the car by bolts 10 and 11, which also pass through 55 the stake and retain the same in the pocket.

The stake-pocket is provided between its ends with a horizontal base-plate 12, extending inward and arranged flush with the upper face of the bottom 13 of the car and provided adjacent to its end 15 with a depending lip or flange 14, which is secured by bolts 15^a to the adjacent intermediate sill 16 of the car. The end 15, which is flanged, rests upon the upper face of the intermediate sill 16, and the 65 flooring of the car is cut out to receive the base-plate.

The base-plate, which is provided with a raised portion 17 adjacent to the stake-pocket, is strengthened by a longitudinal web 18, disposed centrally of its lower face and provided with laterally-disposed horizontal flanges 19. The inner end of the base-plate is thickened where it joins the stake-pocket to increase the strength of the device, and the raised portion 17 is provided for the purpose of supporting the sides of the car, a short distance above the bottom of the same. These flanges 19 extend from the depending lip or flange to the stake-pocket and are supported by transverse vertical flanges 20, located at points between the end 15 of the base-plate and the stake-pocket. The flanges 19 are narrower than the base-plate between the depending lip or flange and the further flange 20, and between the latter and the stake-pocket the horizontal flanges have widened portions 21 of the same width as the base-plate. The depending lip or flange is braced by a centrally-arranged triangular web 22, extending from 90 its lower edge to a point directly beneath the longitudinal web 18. The perforations 23 for the reception of the bolts 15^a are located at opposite sides of the triangular bracing-web 22, as clearly illustrated in Fig. 5 of the accompanying drawings, and the stake-pocket is strengthened around the bolt-openings by annular bosses or enlargements.

The invention has the following advantages: The stake-pocket, which is constructed of malleable iron, is adapted to be readily applied to new and old cars, and by being secured to the side sills and the adjacent intermediate sills in the manner shown it is adapted to

brace the cars, retain the side sills in place, and prevent the sides from bulging out. The flanged base-plate, which extends from the stake-pocket, is flush with the upper face of the bottom of a car, and it presents a construction of great strength and durability.

Changes in the form, proportion, and minor details of construction may be resorted to without departing from the spirit or sacrificing any of the advantages of this invention.

What is claimed is—

1. A device of the class described comprising a stake-pocket designed to be secured to the outer face of a car at the side and side sill thereof, and a base-plate extending inward from the stake-pocket at a point between the ends thereof and provided with a lip or flange arranged to be secured to the adjacent intermediate sill of a car, substantially as and for the purpose described.

2. A device of the class described comprising a stake-pocket, and a base-plate extending inward from the stake-pocket, provided a short distance from its end with a depending flange or lip and having supporting webs and flanges, substantially as described.

3. A device of the class described comprising a stake-pocket, and a base-plate extending inward from the stake-pocket and composed of a top plate, a central longitudinal web, depending from the top plate, the horizontal laterally-disposed flanges arranged at the bottom of the central web and provided adjacent to the stake-pocket, with widened portions, transverse webs connecting the top plate and the horizontal flanges, and a lip or flange depending from the base-plate and having a brace, substantially as described.

ing a stake-pocket, and a base-plate extending inward from the stake-pocket and composed of a top plate, a central longitudinal web, depending from the top plate, the horizontal laterally-disposed flanges arranged at the bottom of the central web and provided adjacent to the stake-pocket, with widened portions, transverse webs connecting the top plate and the horizontal flanges, and a lip or flange depending from the base-plate and having a brace, substantially as described.

4. A device of the class described, comprising a stake-pocket, and a base-plate extending inward from the stake-pocket and having its upper face arranged flush with the bottom of a car, said base-plate being provided, adjacent to the stake-pocket, with a raised portion, 17, adapted to support the sides of the car a short distance above the bottom of the same, substantially as described.
